UNITED STATES PATENT OFFICE.

EDWARD W. NEWELL, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

FRICITION DRAFT-GEAR.

1,286,724.

Specification of Letters Patent.

Patented Dec. 3, 1918.

Application filed September 2, 1915. Serial No. 48,641.

To all whom it may concern:

Be it known that I, EDWARD W. NEWELL, a citizen of the United States, residing at Pittsburgh, in the county of Allegheny and State of Pennsylvania, have invented new and useful Improvements in Friction Draft-Gears, of which the following is a specification.

This invention relates to friction draft gear, and more particularly to a draft gear for cars employed in passenger service.

In the handling of passenger cars, particularly sleeping cars at night, it is desirable to effect the shifting of cars and the like with the least possible jar. If draft gears of the usual high capacity are employed, the gears do not come into action under comparatively light buffing and draft stresses and consequently such stresses may be directly transmitted to the car and cause shocks which annoy and possibly awaken passengers.

One object of my invention is to avoid the above condition by providing a friction draft gear having two stages of action, a preliminary friction movement sufficient to take care of light buffing and draft stresses and a final movement which will provide the usual high capacity to absorb shocks due to heavier buffing and draft stresses.

Another object of my invention is to provide means for centering the coupling which utilizes draft springs employed in the draft gear, so that a separate construction for that purpose is not required.

Another object of my invention is to provide improved means for placing the draft springs under initial compression.

In the accompanying drawings; Figure 1 is a vertical longitudinal section of a friction draft gear embodying my invention, showing the parts in release position; Fig. 2 a horizontal longitudinal section thereof; Fig. 3 a side elevation thereof; Fig. 4 a vertical longitudinal section, showing the parts compressed under a buffing stress; Fig. 5 a transverse section on the line *a—a* of Fig. 1; Fig. 6 a vertical longitudinal section of the draft gear, in part, showing the parts in position before the keys are inserted to place the draft springs under initial compression; and Fig. 7 a transverse section on the line *b—b* of Fig. 1.

According to my invention, the draft gear

may comprise a casing 1 having rearwardly extending side walls 3 connected at the rear end by a wall 4. Within the casing 1 are mounted vertically opposite friction members 24 each having an inclined friction face 2 and rearwardly of the friction members 24 is a rear friction element 5 having oppositely inclined friction faces 6. Centrally of the gear there are arranged front and rear plunger wedges 7 and 8 each having oppositely inclined friction faces and engaging the friction faces of the friction members 24, the friction element 5, and the plunger wedges 7 and 8, are wedge blocks 9. Mounted between the friction element 5 and the rear wall 4 of the casing 1 are draft springs, 70 preferably comprising four sets of similar springs 10 and 11.

Interposed between the end of the usual draw-bar 12 and the front plunger wedge 7 is a front follower 13 which is adapted 75 when the gear is subjected to draft stresses to engage stops 14 secured to the car center sills 15.

For transmitting draft stresses from the draw-bar to the draft gear, links 16 may be 80 employed, the links being operatively connected to the draw-bar by a key 17, extending through elongated slots 18 in the links, which permit independent rearward movement of the key and draw-bar under draft 85 stresses.

Said links extend through slots in the follower plate 13 and the casing 1 and the rear portions thereof are made round and provided with screw threads for nuts 19. Additional draft springs 20 are mounted on the rounded portions of the links 16 between the nuts 19 and a spring plate 21 which is adapted to engage stops 22, secured to the car center sills 15, when the springs 20 are 95 compressed by the forward movement of the links.

The spring plate 21 extends through slots 23 in the side walls 3 of the casing 1, the slots being extended forwardly a certain 100 amount to allow for inequalities in construction and for wear of parts.

The springs 20 may be placed under initial compression by screwing up the nuts 19 and in order to put the set of springs 10 and 11 under initial compression, the casing 1 and the friction members 24 are provided with slots so positioned that when the parts

are first assembled the slots are out of alignment, as shown in Fig. 6 of the drawings.

In order to bring the slots into alignment for the insertion of a locking key 25, it is necessary to force the friction members 24 laterally inward. By this movement, the wedge blocks 9 are forced rearwardly and inwardly to the position shown in Fig. 1 of the drawings and consequently the rear friction element 5 is forced rearwardly, compressing the springs 10 and 11, since the rear ends of the springs are held against movement by the rear wall of the casing 1.

The rear plunger wedge 8 is engaged by 15 a stem 26 which extends to the rear wall 4 of the casing 1.

In operation, when a buffing stress is applied to the draw-bar 12, the follower plate 13 is moved rearwardly and with it the 20 front plunger wedge 7. The rear plunger wedge 8 is held stationary by the engagement of stem 26 with the rear wall 4 of the casing 1, since the casing is prevented from moving rearwardly by engagement with the 25 stops 22.

The wedge blocks 9 are consequently forced rearwardly and laterally outward, causing the rear friction element 5 to move rearwardly, compressing the springs 10 and 30 11, the ultimate position of the parts being shown in Fig. 4 of the drawings. The springs 20 are also compressed by the engagement of the friction element 5 with the spring plate 21 and preferably a certain 35 amount of clearance is provided between the spring plate 21 and the friction element 5, so that there will be a preliminary friction movement against the resistance of the springs 10 and 11 only and then upon engagement of the friction element 5 with the 40 spring plate 21 the resistance of the springs 10 and 11. 20 is added to that of the springs 10 and 11.

By this means, the lighter stresses are taken up without imparting shocks to the 45 car, while a high ultimate capacity is provided by the additional resistance of the springs 20. This clearance space may be varied as desired and may be entirely dispensed with if it should be desired to have 50 the full resisting capacity act at the initial movement of the parts.

Under a draft stress, the links 16 are pulled forward by the draw-bar 12 through the engagement of the key 17 therewith and 55 the casing 1 is moved forward by the engagement of the links with the projections 27 carried by the casing 1 and extending through slots in the links.

The forward movement of the rear wall 4 60 of the casing 1 then compresses the springs 10 and 11, and the spring pressure acting on the rear friction element 5 forces the same forwardly.

Since the front plunger wedge 7 is prevented from forward movement by engage-

ment with the follower plate 13 which is held against forward movement by the stops 14, the wedge blocks will be forced forwardly and laterally outward by the movement of the rear friction element 5.

The friction members 24 move forwardly with the casing 1 and thus provide space for the movement of the wedge blocks 9.

It will be noted that under a draft stress, the springs 20 are compressed by the forward movement of the links 16, but the compressive movement of the springs is not transmitted to the friction elements, since the springs engage the spring plate 21 which is held against forward movement by the stops 22, and consequently only the spring resistance of the springs 20 is effective under draft stresses while the frictional resistance is due entirely to the force of the springs 10 and 11.

The resisting capacity of the draft gear will therefore be less under draft than under buffing stresses.

By providing a clearance space between the projections 27 and the rear walls of the 90 slots in the links 16, as shown, the draft gear will have a preliminary spring movement due to the compression of the springs 20, until the links 16 engage the projections 27, when the casing 1 will be moved to bring 95 the frictional resistance into action. If it is desired to have the frictional resistance act from the start, this may be secured by making the slots in the links without clearance, so that the links will engage the projections 27 as soon as movement takes place.

Another feature of the invention consists in utilizing draft springs for centering the draw-bar, so that a special device for this purpose need not be provided.

In this connection, it will be noted that the links 16 when pulled forward, tend to compress the springs 20. Now if there is any lateral movement of the draw-bar, one or the other of the links 16 will be pulled forward, but since this movement compresses the corresponding spring 20, there is a constant tendency of the springs to return to normal position so that the force of the springs is exerted to maintain the draw-bar 115 in its central position.

So far as the operation of the draft gear is concerned, the friction members 24 could be made integral with the casing 1, and therefore in the claims, the casing 1 and the friction members 24 will be referred to as the front friction element having oppositely inclined friction faces.

Having now described my invention, what I claim as new and desire to secure by Letters Patent, is:-

1. In a friction draft gear, the combination with a casing, friction elements, and draft springs engaging said casing for resisting movement of said friction elements,

of link members, and additional draft springs engaging said link members for also resisting movement of said friction elements.

2. In a friction draft gear, the combination with a casing, friction elements and draft springs engaging said casing for resisting movement of said friction elements, of link members, and additional draft springs engaging said link members for resisting movement of said friction elements after a predetermined initial movement thereof.

3. In a friction draft gear, the combination with a draw-bar, of friction members, draft springs for opposing movement of the friction members under draft stresses applied to the draw-bar, links for transmitting draft stresses from the draw-bar to the draft gear, stops and additional springs mounted 15 on said links and adapted to be compressed against said stops under draft stresses applied to the links.

4. The combination with a draw-bar, of a friction draft gear comprising a casing having front oppositely inclined friction faces associated therewith, a rear friction element having oppositely inclined friction faces, central plunger wedges having oppositely inclined friction faces, wedge blocks having 25 oppositely inclined friction faces adapted to engage the friction faces of the casing and the plunger wedges, main draft springs for opposing movement of the friction members, links operatively connecting the draw-bar to the draft gear, 30 springs for opposing preliminary draft movement of the links, said links being adapted upon a further draft movement to engage the casing and thereby effect the movement of the friction members against 35 the resistance of the main draft springs.

5. The combination with a draw-bar, of a draft gear comprising friction elements and provided with side links for transmitting draft stresses from the draw-bar to the draft 45 gear, and a spring associated with each link for opposing draft movements of the links and tending to maintain the draw-bar in normal position, said springs being adapted

to react on the friction elements of the draft gear.

6. The combination with a draw-bar, of a draft gear comprising friction elements and provided with side links for transmitting draft stresses from the draw-bar to the draft gear, and a separate spring associated with 50 each link and adapted to resist movement of the friction elements and for opposing draft movements of the links, lateral movement of the draw-bar being resisted by the compressive action of the springs.

7. The combination with a draw-bar, of a draft gear comprising friction elements and provided with side links for transmitting draft stresses from the draw-bar to the draft gear and a spring mounted on each link for 55 resisting draft movements and for centering the draw-bar, said springs being interposed between the links and the friction elements.

8. A friction draft gear comprising a casing, front friction members having inclined 60 friction faces, a rear friction element having oppositely inclined friction faces, central plungers having oppositely inclined friction faces, wedge blocks having friction faces adapted to engage the friction faces of the 65 friction members, the friction element and the plungers, springs interposed between the rear friction element and the casing, and keys for securing the front friction members to the casing with the friction parts 70 compressing the springs.

9. A friction draft gear comprising friction members, main draft springs for opposing the initial movement of the friction members under buffing stresses, additional 75 draft springs for opposing further movement of the friction members, and stops for preventing the additional springs from acting to oppose the movement of the friction members under draft stresses.

In testimony whereof I have hereunto set my hand.

EDWARD W. NEWELL.
